UNITED STATES PATENT OFFICE.

LOUIS N. D. WILLIAMS, OF OGONTZ, PENNSYLVANIA.

TRANSFERRING DEVICE FOR KNITTED WEBS.

Application filed December 14, 1922. Serial No. 606,790.

To all whom it may concern:

Be it known that I, LOUIS N. D. WILLIAMS, a citizen of the United States, residing at Ogontz, county of Montgomery, and

5 State of Pennsylvania, have invented certain new and useful Improvements in Transferring Devices for Knitted Webs, of which the following is a specification, reference being had to the accompanying drawings.

10 This invention relates to knitting and more particularly to the transfer of knitted webs.

An object of the invention is to generally improve that type of transfer ring used in 15 applying stitches to the needles of a knitting machine in such operations, for example, as the "running-on" of a rib top of a half hose preparatory to the knitting of the plain web of the leg and foot, and particularly to that specific type of transfer ring in which stitch strippers are employed in connection with the stitch carrying points or quills for the purpose of stripping the 20 stitches from the points or quills and transferring them to the needles of the knitting machine after the transfer ring has been 25 properly positioned in cooperative relation or engagement therewith.

Transfer rings of this type, as heretofore 30 constructed, have been equipped with stitch strippers which were operable in unison to simultaneously transfer all of the stitches from the points or quills to the needles. In certain cases it will be desirable to avoid 35 this simultaneous transfer of stitches and the object of my present invention is to so construct a transfer ring of the type specified that the stitch strippers will be operable individually, and in succession, to produce 40 a correspondingly individual and successive transfer of stitches from the points or quills of the transfer ring to the needles of the knitting machine.

This object I accomplish in the manner 45 hereinafter set forth, reference being had to the accompanying drawings, in which—

Figure I is a top or plan view of a transfer ring constructed in accordance with the present invention;

50 Figure II is a vertical sectional view of the same, illustrating its manner of application to the needles of a knitting machine;

Figure III is a view similar to Figure II showing the positions of the parts assumed 55 at the beginning of the transferring operation;

Figure IV is a horizontal sectional view on the line IV—IV, Figure II; and

Figure V is a vertical sectional view on the line V—V, Figure III.

Proceeding to a detailed description of my invention, 1 indicates a circular frame having an annular head 2 from which project a circular series of stitch carrying points or quills 3. Upon the frame 1 are 60 slidably mounted a series of stitch strippers, each embodying a stem 6 and an angularly directed stripping finger 7. The stripping fingers extend between the points or quills 3 (which are for convenience herein-after referred to simply as "quills") and are adapted to be projected or lowered to strip the stitches carried by the quills therefrom and transfer them to the needles 8 of the knitting machine. In Figures II and 65 III of the drawings only those quills, needles and strippers at diametrically opposite sides are illustrated, in order to avoid unnecessary confusion in the views.

Mounted upon the frame 1 and encircling 70 the stems 6 of the stitch strippers is a cam ring 9 provided with a raceway 10 into which project bits 11 formed upon the stems 6; and slidably mounted in the ring 9 so that it may be caused to project into the 75 raceway 10 is a cam 12 having an inclined face 13.

When the transfer ring with fabric upon it is to be applied to the needles of a knitting machine, the strippers are retracted, as 80 shown in Figure II, and the bits 11 on the stems 6 occupy the rearmost part of the raceway 10. At this time the cam 12 is also retracted, as shown in Figure II and by dotted lines, in Figure V. The ring is then applied to the needle bank, each quill 3 with stitch α upon it being brought into cooperative relation or engagement with the corresponding needle 8, as shown in Figure II.

The cam 12 is now projected or lowered 100 into the raceway 10, as shown in Figure III and, by full lines, in Figure V, engaging the bits 11 which are in its immediate path of movement with corresponding projection of stripper fingers 7, as shown in Figure III. The stitches controlled by the projected stripper fingers are stripped from the quills and impaled over and upon the needles, and, with the cam 12 maintained in projected position, the cam ring 9 is rotated about the frame 1 of the transfer ring. During its circuit, the inclined face 105 110

13 of the cam 12 strikes and projects the various bits 11 individually and in succession with corresponding individual and successive projection of the various strippers 6 and consequent individual and successive transfer of stitches from the quills to the needles. After the circuit of the cam 12 is completed the fabric is entirely transferred from the ring to the knitting machine and 10 the empty ring may be removed.

The cam ring 9 may be maintained in proper relation to the circular frame 1 by any suitable connecting means, that which I have illustrated consisting of pins 14 carried by the frame 1 and projecting into an annular groove 15 in the inner face of the cam ring.

Mechanism of any available type may be used for controlling the position of the cam 20 12 and for rotating the cam ring 9 about the frame 1. That which I have illustrated consists of a transverse bridge 16 secured to opposite sides of the cam ring and provided with a pivotally mounted swinging 25 plate 17, the latter having a manipulating handle 18 and also a projecting finger 19 adapted to engage with either of slots 20 or 21 in one side of the cam 12. The finger 19 normally engages the lower slot 20, as 30 shown in Figures I and II, thereby holding the cam 12 in the raised or retracted position. When it is desired to project the stitch strippers, the finger 19 is released from the slot 20, the cam 12 projected to 35 the position shown in Figure III, and the finger 19 engaged with the slot 21 to maintain the cam in projected position during its circuit. The handle 18 on the plate 17 is grasped and pushed in the direction of 40 the arrow in Figure I, and the cam ring 9 is thereby caused to rotate about the frame 1, the cam 12 moving in the direction of the arrow in Figure V.

In order to ensure positive alignment 45 of the points or quills 3 and the needles, I may provide a projection 22 capable of engaging a stop 23 on the fixed portion of the knitting machine frame. By virtue of this provision, the transfer device will be 50 held against rotation during the manipulation of the handle 18 in the transfer of the stitches.

Furthermore, although I have described the transfer as accomplished manually it is to be understood that I do not limit myself 55 to hand operation. The ring and its parts may readily be constructed so as to be engaged and operated by means of suitable handling or automatic mechanism.

Having thus described my invention, I claim:

1. In a web transferring device, the combination of a series of stitch quills adapted to be engaged simultaneously with all the needles of a knitting machine, stitch strippers individually associated with the quills, and means for actuating the strippers to successively transfer the stitches between the quills and the needles.

2. In a web transferring device, the combination of a frame with stitch quills adapted to be held stationary with respect to the needles of a knitting machine, stitch strippers individually associated with the quills, and means for actuating the strippers to 75 successively transfer the stitches between the quills and the needles.

3. In a web transferring device, the combination of an annular frame with stitch quills adapted to be held stationary with respect to the needles of a knitting machine, stitch strippers individually associated with the quills, and means rotatable on the frame for actuating the strippers to successively transfer the stitches between the quills and 85 the needles.

4. In a web transferring device, the combination of an annular frame with stitch quills adapted to be held stationary with respect to the needles of a knitting machine, 90 stitch strippers individually associated with the quills, a ring rotatable on said frame, and means carried by the ring for actuating the strippers to successively transfer the stitches between the quills and the 95 needles.

In testimony whereof, I have hereunto signed my name at Philadelphia, Pennsylvania, this 12th day of December, 1922.

LOUIS N. D. WILLIAMS.
